UNITED STATES PATENT OFFICE

2,555,789

BILFFOLD HAVING A LOCKING TAB

George W. Durham, Salem, Oreg.

Application March 10, 1947, Serial No. 733,668

1 Claim. (Cl. 150—38)

The present invention relates to new and useful improvements in billfolds and has for its primary object to provide foldable pocket-forming flaps at the side edges of the back of the billfold and including a flap substantially coextensive with the back to form a bill compartment and providing a locking tab of novel construction for the bill compartment.

A further object of the invention is to otherwise structurally improve the billfold and which, at the same time, is neat and attractive in appearance, relatively inexpensive to manufacture and well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a plan view of the inside of the billfold in open position.

Figure 2 is a perspective view of the billfold in partly open position.

Figure 3 is a longitudinal sectional view taken on a line 3—3 of Figure 1.

Figure 4 is a plan view of the blank from which the billfold is constructed.

Figures 5 and 6 are plan views of the removable tongues, and

Figure 7 is a front elevational view of one of the identification tags.

Referring now to the drawings in detail wherein for the purpose of illustration I have disclosed a preferred embodiment of the invention the numeral 5 designates the blank of leather or other suitable material from which the billfold is constructed and which includes the body 6 of substantially rectangular form and which forms the back or outer wall of the billfold and at one longitudinal edge of which is formed a flap 7 foldable upon the body 6 along the fold line 8 to form a bill compartment. A longitudinal slot 9 is formed in the flap 7 adjacent the fold line 8 and to the edges of which a slide fastener 10 of conventional construction is secured.

The central portion of the opposite longitudinal edge of the body 6 is formed with a substantially T-shaped tab 11 adapted for engaging slits 12 in the flap 7 to secure the flap in its folded position against the body 6.

At each side of the tab 11 the body 6 is formed with elongated laterally extending flaps 13, the outer half of the flaps 13 being foldable upon themselves along the fold line 14 and the inner

2

half of the flaps 13 are foldable upon the body 6 along the fold lines 15 and outwardly against the flap 7 to form pockets 16 and 17 at each end of the billfold.

5 The ends of the body 6 are provided with flaps 18 and 19 foldable along the lines 20 and 21 respectively, the outer ends of the flaps 18 and 19 being formed with T-shaped locking tabs 22 and 23 respectively. The flaps 18 and 19 thus close 10 the outer edges of the pockets 16 and 17 while the inner edges thereof are open.

After the flaps 18 and 19 have been folded inwardly against the pockets 16 and 17 the same are secured in position by elongated metal tags 26 having bendable T-shaped tabs 27 bent around the edges of the narrow portions of the tabs 22 and 23 and inserted in the slits 24 and 25 of the pockets 16 and 17 to thus secure the flaps 18 and 19 in a closed position against the outer surfaces 20 of the pockets 16 and 17 and to thus close the outer edges of said pockets while the inner edges thereof remain open.

The tags 26 may carry suitable identification indicia 28 to identify the owner of the billfold.

Tongues of a type shown at 29 in Figure 5 of the drawings and at 30 in Figure 6 of the drawings may have their ends inserted behind the pockets 16 and 17 to provide additional compartments and one end of the tongue 30 is reduced as shown at 31 for insertion under one of the tags 26 as shown at the left hand side of Figure 1 of the drawings. The reduced end of the tongue 30 thus serves as a flap 32 to close the inner edge of the pocket 16 and which is retained in closed position by the identification tag.

35 The pocket 17 may hold a memo pad or the like 33.

In view of the foregoing description taken in conjunction with the accompanying drawings it is believed that a clear understanding of the device will be quite apparent to those skilled in this art. A more detailed description is accordingly deemed unnecessary.

It is to be understood, however, that even 45 though there is herein shown and described a preferred embodiment of the invention the same is susceptible to certain changes fully comprehended by the spirit of the invention as herein described and the scope of the appended claim.

I claim:

In a billfold, the combination of a rectangular shaped body portion forming a back, a flap at one longitudinal edge of the body foldable thereon to form a compartment, said flap having a pair of 50 slits, a substantially T-shaped tab at the opposite

longitudinal edge of the body and engaged in said slits to secure the flap in folded position, foldable flaps at the ends of the body portion overlying the first-named flap and closing the ends of the compartment formed thereby, and means holding the end flaps in closed position.

GEORGE W. DURHAM.
